(57) **CLAIM**

The ornamental design for a rear bumper spoiler, as shown and described.

DESCRIPTION

FIG. 1 is a perspective view of a rear bumper spoiler in accordance with the present invention;

FIG. 2 is another perspective view of the rear bumper spoiler of FIG. 1;

FIG. 3 is a rear perspective view of the rear bumper spoiler of FIG. 1;

FIG. 4 is a front elevation view of the rear bumper spoiler of FIG. 1;

FIG. 5 is a top plan view of the rear bumper spoiler of FIG. 1;

FIG. 6 is a bottom side view of the rear bumper spoiler of FIG. 1; and,

FIG. 7 is a right side elevation view of the rear bumper spoiler of FIG. 1, wherein a left side elevation view is a mirror image thereof.

CERTIFICATE OF CORRECTION

PATENT NO. : Des. 540,226 S
APPLICATION NO. : 29/257993
DATED : April 10, 2007
INVENTOR(S) : Todd Levy

Page 1 of 9

It is certified that error appears in the above-identified patent and that said Letters Patent is hereby corrected as shown below:

The title page showing the illustrative figure should be deleted and substitute with the attached title page.

The drawing sheet, consisting of Fig. 1-7, should be deleted and replaced with drawing sheet, consisting of Fig. 1-7, as shown on the attached page.

Signed and Sealed this

Eighteenth Day of September, 2007

JON W. DUDAS
Director of the United States Patent and Trademark Office
